UNITED STATES PATENT OFFICE

157,608

FRAME FOR A WIRE RECORDER OR
SIMILAR APPARATUS

William P. Lear, Santa Monica, Calif., assignor to
Lear, Incorporated, Grand Rapids, Mich., a
corporation of Illinois

Application May 5, 1948, Serial No. 146,193

Term of patent 14 years

(Cl. D26—14)

To all whom it may concern:

Be it known that I, William P. Lear, a citizen of the United States, residing at Santa Monica, in the county of Los Angeles and State of California, have invented a new, original, and ornamental Design for a Frame for a Wire Recorder or Similar Apparatus, of which the following is a specification, reference being had to the accompanying drawing, forming a part thereof, in which:

Fig. 1 is a top plan view of a frame for a wire recorder or similar apparatus showing my new design;

Fig. 2 is a front elevational view of the same;

Fig. 3 is a right side elevational view of the same, the left side being symmetrical therewith;

Fig. 4 is a cross-sectional view, somewhat enlarged, taken on the line 4—4 of Fig. 2; and

Fig. 5 is a perspective view of the frame, showing my new design.

I claim:

The ornamental design for a frame for a wire recorder or similar apparatus, substantially as shown.

WILLIAM P. LEAR.
